(57) **CLAIM**

The ornamental design for a powder dispenser cover with angled nozzle, as shown and described.

DESCRIPTION

FIG. 1 is a bottom right perspective view of a first embodiment of a powder dispenser cover with angled nozzle of the present invention;

FIG. 2 is a front side view thereof;

FIG. 3 is a back side view thereof;

FIG. 4 is a left side view thereof;

FIG. 5 is a right side view thereof;

FIG. 6 is a top view thereof;

FIG. 7 is a bottom view thereof;

FIG. 8 is a bottom right perspective view of a second embodiment of a powder dispenser cover with angled nozzle of the present invention;

FIG. 9 is a front side view thereof;

FIG. 10 is a back side view thereof;

FIG. 11 is a left side view thereof;

FIG. 12 is a right side view thereof;

FIG. 13 is a top view thereof;

FIG. 14 is a bottom view thereof;

FIG. 15 is a bottom right perspective view of a third embodiment of a powder dispenser cover with angled nozzle of the present invention;

FIG. 16 is a front side view thereof;

FIG. 17 is a back side view thereof;

FIG. 18 is a left side view thereof;

FIG. 19 is a right side view thereof;

FIG. 20 is a top view thereof; and,

FIG. 21 is a bottom view thereof.

In the drawings, the broken lines depict environmental subject matter only that forms no part of the claim.
